UNITED STATES PATENT OFFICE.

SAMUEL H. WHEELER, OF CHICAGO, ILLINOIS, ASSIGNOR TO THE WHEELER & WILSON MANUFACTURING COMPANY, OF BRIDGEPORT, CONNECTICUT.

RETAINING DEVICE FOR SEWING-MACHINE COVERS.

SPECIFICATION forming part of Letters Patent No. 557,925, dated April 7, 1896.

Application filed March 2, 1894. Serial No. 502,096. (No model.)

To all whom it may concern:

Be it known that I, SAMUEL H. WHEELER, of Chicago, county of Cook, State of Illinois, have invented an Improvement in Retainers for Sewing-Machine Covers, of which the following description, in connection with the accompanying drawings, is a specification, like letters and figures on the drawings representing like parts.

- 10 Many users of sewing-machines require a cover to protect the head of the machine when not in use, and these covers, made of wood, are usually provided with lugs or feet to enter sockets in the top of the cabinet and have 15 locks to engage a lock-plate also attached to the said top. I desire to dispense with the sockets and lock-plate which have to be let into the top of the cabinet and also to dispense with the usual lock and the lugs or 20 feet. To effect this object, I have provided the cover with a retaining device that engages a portion of the top of the machine rather than a part of the cabinet or its top or the cloth-plate or foot-plate of the machine.
- 25 My invention may be carried out in many different forms, as will be hereinafter described.

My invention consists, essentially, in the combination, with the upper part of the head 30 of a sewing-machine and its cover, of a retaining device to connect said cover to said head.

Figure 1 is a partly sectional elevation of one form of sewing-machine head and cover and cover-retainer containing my invention. Fig. 2 is a section on a smaller scale in the line α , Fig. 1, looking to the left; Fig. 3, a section on the same line, looking to the right; Fig. 4, a section below the line α' , Fig. 1, with 35 the wheel in elevation; and Figs. 5 to 9, inclusive, are transverse sections of the upper parts of a cover and sewing-machine head, illustrating as many different modifications of my invention. Fig. 10 is a longitudinal section 40 of portion of a cover and an elevation of part of the arm of a sewing-machine, illustrating still another modification of my invention; and Fig. 11 is a side elevation of a modified form of spool-pin used in one form 45 of my cover-retainer.

Referring to the drawings, A represents the top of a sewing-machine cabinet, it in practice being supported upon any usual legs, (not shown); B, the head of a sewing-machine, and C the cover to completely inclose said head. These parts are and may be all as usual.

The lower edges of the cover will in practice be provided with india-rubber or other non-metallic buffers a , which will simply rest 60 on the top of the table, their use being solely to prevent marring the finish of the top.

The cover is in no way directly connected with the table or with the cloth-plate or foot-plate of the machine.

The cover contains within it, near one end, a crotch or bar b^{12} , which embraces snugly a part of the overhanging arm of the head, preferably near its end, and at the opposite end of the cover there are two like lugs b^{13} , having at their inner sides two grooves to embrace a part of the usual balance-wheel a^2 of the machine. These devices b^{12} b^{13} are very desirable and aid in preventing any twisting 70 of the cover on or with relation to the head 75 of the machine, and, while they do not lock the cover to the machine, each or both constitute positioning devices for the cover.

As stated, the chief object of my invention is to provide the cover with a retaining device which, co-operating with the machine-head or a part mounted thereon wholly above the cloth-plate or bed of the machine, will 80 keep the cover in place.

In the form of my invention illustrated in 85 Fig. 1, b constitutes a retaining device, represented as a bent or cranked rod, one end of which is exposed to be engaged by a suitable key b' , (shown best in Fig. 3,) said key being, preferably, one with a shank other than round 90 to engage a correspondingly-shaped recess of the retaining device, or the converse would operate equally as well.

In Fig. 1 the head of the machine has fixed upon it a stand b^2 , upon which is pivoted at 95 b^3 a spool-pin b^6 , said spool-pin thus being attached to and forming a part of the head, the spool-pin having fixed to it in turn a block or projection b^7 , which is adapted to be engaged by the retaining device. The form in which 100

I have represented my invention in Fig. 1 is quite desirable; but my invention may be carried out in many other ways by the exercise only of mechanical skill, and I propose now 5 to show some of these different ways.

Referring to Fig. 11, I have shown a modified form of spool-pin b^8 , it having a shoulder b^{10} , with which may coöperate the retaining device b .

- 10 It will be understood that when the retaining device is turned aside, as in dotted lines at the right in Fig. 1, so that its cranked part is free from the influence of the projection or shoulder, however located on the machine-15 head above the cloth-plate, the cover may readily be lifted off the head of the machine; but when the cover is to be kept in place the retaining device will be turned until its cranked portion engages the under side of 20 the block or projection, the retaining device being under the control of the key.

In the modification Fig. 5, D is supposed to represent part of the overhanging arm of the head of the machine, and D' the cover, 25 having a stand or bracket D^2 , through which is extended a rock-shaft D^3 , having a projecting finger D^4 , which enters a slot in or engages a part of the overhanging arm, said shaft D^3 being under the control of a suitable 30 key, which may be put through a suitable keyhole at the top of the cover.

In the modification Fig. 6, F represents the cover, and F' may represent the overhanging arm of the head of the machine, and f the retaining device, it being represented as an L-shaped finger connected with a short rock-shaft f' , adapted to be engaged by a key and turned into the dotted-line position when the cover is to be removed and to occupy the full-40 line position when the cover is to be fastened to the head of the machine.

In the modification Fig. 7, G may represent the cover; G' , the overhanging arm of the head of the machine, the retaining device consisting, essentially, of a spring g , having a shoulder g' , a pull-key g^2 in the shape of a rod being connected with said spring-like retaining device to pull the same away from under the overhanging arm when it is desired to remove 50 the cover, the spring readily passing the overhanging arm when the cover is being applied to the head of the machine and slipping automatically under the said arm.

In the modification Fig. 8, I represents the 55 cover; I' , part of the overhanging arm of the machine; i , a dog pivoted at i^2 upon one end of a spring-arm i' , attached at i^2 to the under side of the cover, a second spring i^3 , having a buffer 3, being joined to the interior of the 60 cover at 4. i^5 represents a rock-shaft mounted in suitable bearings and shaped at one end to be engaged, as described, by a key, said rock-shaft having fast upon it a cam 6, suitably shaped so that when the rock-shaft is 65 turned by the key into the full-line position its cam 6 will act upon the upper end of the

retaining device i and cause the lower end of said retaining device i to engage a portion of the head of the machine—as, for example, the overhanging arm I' . When the cam 6 is not 70 forced against the retaining device, as indicated by the dotted lines, in the direction indicated in Fig. 8, then the upper end of the retaining device will be moved in the direction of the arrow near it by a suitable spring 75 12, connected at one end with the pivot 2 and acting upon a pin or projection at one side of the retaining device, the retaining device when freed from the influence of the cam 6 occupying the dotted-line position shown in 80 Fig. 8.

Fig. 9 shows yet another modification, wherein the retaining device m is shown as a dog mounted upon a short rock-shaft m' , supported just inside the end of the cover, said 85 rock-shaft being accessible, as described of the retaining device in Fig. 1, by a key from outside the cover.

In the modification Fig. 9 the circular line m^4 is supposed to represent the inner hub end 90 of the hand-wheel of the machine, and m^5 two guides connected to the inside of the cover and acting on either side of the hub of the hand-wheel, said retaining device when in the position Fig. 9 serving to lock the cover in 95 place; but the retaining device may be turned over to the left by the key, thus freeing the retaining device from the head of the machine.

In Fig. 10, n is supposed to represent the 100 cover, and n' the head of the machine, said head having a projection n^2 , which is adapted to be engaged by a spring-controlled retainer n^3 , herein represented as an elbow-lever, the spring n^4 supported at one end on the cover 105 and acting at its other end against the inner end of the retaining device causing the same normally to engage the projection n^2 , and to remove the cover the operator will push down upon the raised end of the retainer, thus 110 removing its inner end from engagement with the projection n^2 .

The retaining device, besides acting as a lock to prevent the lifting of the cover, also, by striking against a part attached to or forming part of the head, serves as one member of a stop to determine the longitudinal position of the cover on the head of the machine, so that the inner end of the cover will not contact with the ends of the head in attempts to 120 put the cover squarely on the machine and cover its bed-plate.

I do not claim a sewing-machine cover provided at its lower end with a catch to engage a projection forming part of the top of the 125 table or of the cloth-plate or of the foot part or plate of the machine; but in my invention the cover-retaining device is arranged within the upper part of the cover and engages some portion of or upon the upper parts of the 130 machine-head.

Having described my invention, what I

claim as new, and desire to secure by Letters Patent, is—

A sewing-machine-inclosing cover provided at or near its upper part with a retaining device adapted to engage a shoulder or projection at the upper end of the sewing-machine head wholly above the cloth-plate of the sewing-machine, substantially as described.

In testimony whereof I have signed my name to this specification in the presence of 10 two subscribing witnesses.
